UNITED STATES PATENT OFFICE.

WILLIAM S. DE CAMP, OF CHILLICOTHE, OHIO.

TRAIN-PIPE-TESTING DEVICE FOR AIR-BRAKES.

SPECIFICATION forming part of Letters Patent No. 758,427, dated April 26, 1904.

Application filed January 19, 1904. Serial No. 189,682. (No model.)

To all whom it may concern:

Be it known that I, WILLIAM S. DE CAMP, a citizen of the United States, residing at Chillicothe, in the county of Ross and State of Ohio, have invented a new and useful Improvement 5 in Train-Pipe-Testing Devices for Air-Brakes, of which the following is a specification.

In the ordinary air-brake system there is a continuous train-line pipe coupled by hose-sections between the cars and also a smaller whistle-pipe running continuously through the train and connected by smaller hose-sections between the cars. These two pipes are provided in their length with angle-cocks in 15 the train-line pipe and stop-cocks in the whistle-pipe, which are required to be opened between cars and to be closed at the end of the last car of the train, and these cocks are ordinarily operated by the brakemen, who sometimes forget to properly open them, and when any intermediate cock in these pipes is left closed it is obvious that the cars in rear of the closed cock are cut off from the engineer, so that he cannot put on the air-brakes nor 25 receive a whistle-signal from that portion of the train.

My invention has for its object to enable the engineer to test the line of train-pipes and whistle-pipes and to ascertain from his cab if 30 all the intermediate angle-cocks of the train-pipe are open and all the intermediate stop-cocks of the whistle-pipes are also open, and to do this I provide a novel form of portable test device to be hung up on the rear end of 35 the last car of the train and to be connected to both the hose of the train-pipe and whistle-pipe and arranged to be operated by an increase of pressure above the normal thrown into the train-pipe by the engineer, which increased pressure will act through all of the 40 train-pipe and through my testing device at the end of the train and will open a vent for the whistle-pipe, and thereby blow a whistle, and thus enable the engineer to ascertain from his cab if all the cocks are open and the air-brake train-pipe and whistle-pipe are in proper 45 operative condition, for if any intermediate angle-cock of the train-pipe is closed or any intermediate stop-cock of the whistle-pipe is closed the whistle will not be blown.

Figure 1 is a perspective view of my portable testing device shown hung upon any suitable support on the rear end of the last car of a train and connected to the rear ends of the train-pipe and whistle-pipe. Fig. 1^a is a detail, and Fig. 2 is an enlarged vertical longitudinal section, of the valve mechanism of my testing device.

In the drawings, A represents the hand-rail or any other suitable portion of the rear 60 end of the last car of a train upon which my portable testing device is detachably hung.

B B' is the rear hose end of the train-pipe, in which train-pipe compressed air of a pressure of about seventy pounds is normally 65 maintained and through which by a reduction of pressure the air-brakes are applied in a well-known way. C C' is the rear hose end of the whistle-pipe, in which compressed air at about forty pounds pressure is maintained 70 and through which by a reduction of pressure the whistle is blown in a well-known way. To the ends of these sections of hose my testing device is coupled, as shown, so as to combine these two factors of an air-brake system 75 and render them co-operative in effect and under the control of the engineer. The objective result is to enable the engineer to blow the whistle by increasing the normal pressure in the train-pipe to, say, ninety or ninety-one 80 pounds and to make it possible for him to do this only when all the angle-cocks in the train-pipe between the locomotive and rear end of the train are open and all the stop-cocks of the whistle-pipe between the locomotive and 85 the rear end of the train are open, so that if the engineer is unable to blow the whistle by such increase of pressure in the train-pipe he knows that there is a cock in either the train-pipe or whistle-pipe which has been accidentally 90 left closed and is not "cut in." In such a contingency the train must be stopped and the closed cock located and opened or cut in, so that the air-brake and signal system may be complete and operative to the end of the 95 train. It will be understood that these cocks of the train-pipe and whistle-pipe being manually operated by the brakemen are liable to be forgotten by the brakeman, and if the air-brakes or signal system are rendered inopera- 100

tive by this forgetfulness serious disaster may follow.

The means by which the engineer is enabled to test and confirm to his own satisfaction the operativeness of his entire system of air-brakes and signals will now be described.

D D' D² D³, Fig. 1, is a vertical pipe composed of several sections, with T-couplings

- 10 D D² D³. This vertical pipe is tightly connected by a suitable clamp with the rear hose end B of the train-pipe. Offsetting from the T-couplings D and D³ are two pipe connections e and e². Of these e is merely a support 15 and may be made solid, while e² forms a passage-way for air from the train-pipe to my valve mechanism. This valve mechanism is shown at E E' E² in vertical position beside and parallel with the pipe D D' D² D³, being 20 supported by the lateral connections ee². The lower end of my valve mechanism is tightly connected by a clamp to the hose end C of the whistle-pipe, which extends through the train. The part E² of the valve mechanism is an old 25 form of diaphragm pin-valve which opens above a predetermined pressure, such as any pressure above the normal pressure of seventy pounds in the train-pipe. Its internal construction is seen in Fig. 2, in which b is a pin- 30 valve which closes on a subjacent seat and shuts off normally the communication between the lateral pipe e² from the train-line and the vertical passage-way d, leading to the valve mechanism E' below. The pin b is carried 35 by a piston 42, which is attached to a diaphragm a, secured at its edges to the stationary casing. The piston is forced down by a coil-spring 41 within a casing 38, and its tension is regulated by a screw-plug 40, sur- 40 mounted by a screw-cap 39, the same being a well-known construction of diaphragm pin- 45 valve, which is normally held closed by the spring, but which when an excessive pressure is admitted beneath the diaphragm is raised by the pressure of the air under the diaphragm and the passage-way d is opened to the lateral pipe e². The nipple of the passage-way d of the diaphragm-valve communicates at the bottom with a screw-cap 1, which detach- 50 ably closes a casing 2, which in turn is screwed into a subjacent cup 3, that connects with the coupling E, leading to the hose end C of the whistle-pipe. The casing 2 has in its side near the bottom a series of vent- 55 openings 8 and has a bottom with a central perforation surrounded by a standing flange on the upper side and a valve-seat 7 on the lower side. Within the casing 2 fits and slides vertically a piston 4, having rigidly at- 60 tached to it a valve-stem 5, which passes through the bottom of the casing and bears on its lower end a valve 10, that closes upwardly on the valve-seat 7. A coil-spring 6 surrounds the valve-stem and normally holds 65 the piston 4 up and the valve 10 closed against

the valve-seat 7. The valve-stem 5 is flattened on two or more of its sides or has a passage-way along its length where it passes through the bottom of the casing 2, so that when the valve 10 descends from the seat 7 70 there is open communication from the space in the cup 3 along said passage-ways up to the top side of the bottom of the casing 2 and to the outlet-vents 8.

The operation of my testing device is as follows: After the train is coupled up and ready to start if the engineer wishes to test the air-brake and signal system he throws a pressure on the train-pipe of, say, ninety pounds, which is twenty pounds more than the normal. This, 75 acting through the hose B and pipes D to D³, enters the diaphragm-valve through lateral pipe e² and lifts the pin-valve b. The air-pressure then passes down passage-way d to the top of piston 4 and forces it down. As 80 soon as valve 10 leaves its seat 7 the air-pressure of forty pounds in the whistle-pipe rushes up through hose C to cup 3 and up the passage-ways 9 to casing 2 and thence issues through the outlets 8 into the air, involving 85 a reduction of pressure in the whistle-pipe that blows the whistle. It is obvious that if any cock in the train-pipe or any cock in the whistle-pipe has not been properly cut-in or opened the influence of the air-pressure 90 would not be felt back of this closed cock, and the test apparatus would not work, and the engineer would know at once that one or more of the cocks in the train-pipe or whistle-pipe was not properly cut-in. When the increased pressure is applied to the train-pipe, 95 the whistle is blown as soon as valve 10 leaves the seat 7; but as the piston 4 continues to descend until it reaches the bottom of the casing 2 it will be seen that the piston passes 100 over and closes the vents 8, and thus stops the blowing of the whistle; but when the increased air-pressure in the train-pipe is taken off the piston 4 starts to rise from the expansion of spring 6, and as soon as the piston 4 rises 105 above the vents 8 the air from the whistle-pipe is again allowed to escape for a moment and the whistle is again sounded, so that there is always a double signal given, one in applying 110 and the other in removing the increased air-pressure. As the piston rises the air above it passes up through passage d and out through the lateral vent c below the pin-valve.

My device as thus described may be hung 115 up or supported in any suitable way at the rear end of the train either inside or outside of an inclosure. A simple and convenient way to support it is shown in the drawings, in which a gooseneck-pipe D⁴ is connected to the upper end of the vertical pipe D to D³, and this gooseneck is simply hung upon the hand-rail A or any other convenient support. At the base of this gooseneck there is a cock D⁴ for opening the train-pipe into the outer air 120

through the gooseneck, so that a brakeman in backing up a train may by opening this cock reduce the pressure in the train-pipe and apply the brakes from this end of the 5 train. A pipe F' is also tapped into a coupling D² of the train-pipe extension and is provided with a valve F and a whistle F², so that the brakeman in backing up may blow for "danger" at this end of the train as well as 10 apply the brakes.

In carrying out my invention I do not confine myself to the exact construction and arrangement of parts, as many variations or modifications may be made without departing 15 from my invention.

To facilitate the application of my device, it is permanently connected to the sections B and C of the hose, and these sections are quickly coupled to the sections B' C' in the 20 usual manner of coupling hose ends between cars.

Having thus described my invention, what I claim as new, and desire to secure by Letters Patent, is—

25 1. A testing device for an air-brake and signal system, consisting of a valve mechanism constructed to connect the air-brake pipe and whistle-pipe at their rear ends, by which the signal-whistle is operated through the air-brake pipe when both are in operative condition, and a rear signal-whistle located in that 30 portion of the device directly connecting with the air-brake pipe to signal danger in backing up the train substantially as described.

35 2. A testing device for an air-brake and signal system, consisting of a valve mechanism constructed to connect the air-brake pipe and whistle-pipe at their rear ends, by which the signal-whistle is operated through the air-brake pipe when both are in operative condition, the connection for the air-brake pipe be- 40

ing extended in the form of a hooked pipe provided with a releasing-valve for applying the brakes, said hooked pipe subserving the double function of a discharge for the air and 45 means for hanging up the testing device substantially as described.

3. A testing device for an air-brake and signal system, consisting of a valve mechanism connecting the air-brake pipe and whistle-pipe at their rear ends, said valve mechanism comprising a pressure-valve to be operated by an increased pressure and a pneumatically-operated discharge-valve for the whistle-pipe 50 substantially as shown and described. 55

4. A testing device for an air-brake and signal system, consisting of a valve mechanism connecting the air-brake pipe and whistle-pipe at their rear ends, by which the signal-whistle is operated through the air-brake pipe 60 when both are in operative condition, said valve mechanism comprising a pressure-valve to be operated by an increased pressure and a pneumatically-operated discharge-valve for the whistle-pipe, said discharge-valve being 65 arranged to sound the whistle twice, once in applying the pressure and once again in releasing pressure substantially as described.

5. In a testing device of the kind described, the combination with a pressure-valve ar- 70 ranged to open as described and a pneumatically-operated discharge-valve comprising a casing with outlet-vents and a bottom with a hole through it, a spring-held piston with attached valve-stem and valve, said valve-stem 75 having a passage-way for air to transmit air to the discharge-vents when the valve opens substantially as described.
